[57] CLAIM

The ornamental design for a corrugated sheet material pallet, as shown and described.

DESCRIPTION

FIG. 1 is a top perspective view of a corrugated sheet material pallet showing my new design;

FIG. 2 is a front elevational view thereof, the rear being a mirror image;

FIG. 3 is a bottom view thereof; and,

FIG. 4 is a left side view thereof, the right side being a mirror image.

Fig. 1

Fig. 2
